UNITED STATES PATENT OFFICE.

CHARLES THOMAS, OF JOLIET, ILLINOIS.

SHAFT-BOXING.

1,082,293.

Specification of Letters Patent. Patented Dec. 23, 1913.

Application filed August 5, 1912. Serial No. 713,263.

To all whom it may concern:

Be it known that I, CHARLES THOMAS, a citizen of the United States, residing at No. 107 Catalpa street, Joliet, in the county of Will and State of Illinois, have invented a new and useful Shaft-Boxing, of which the following is a specification.

My invention is adaptable to shafts of all kinds, but is especially intended for use in 10 automobiles and for crank-shafts in automobiles.

The objects of my invention are, by a combination of mechanisms, to maintain the correct relative dimensions of the cylinder of 15 the box and the shaft journaled therein, notwithstanding the wear on the surfaces of the cylinder and the shaft, and thus to take up increase of space caused by friction, and increase the durability and length of time the 20 box and shaft can be satisfactorily used.

In the accompanying drawing—Figure 1 is a perspective view of the shaft-box before being used; Fig. 2 is a perspective view of the same after being used for nearly the full 25 period of satisfactory use; and Fig. 3 is a view of one of the twin wedges.

Frame 1 of the shaft box, especially when the shaft is a crank-shaft, is integral with, or connected to, the end of some connecting rod, as shown. The cylinder 10, of the box, is sunk about half into the bottom part of frame 1. The cap 2 fits in between the side walls of frame 1 and down over the shaft, and when both shaft and box are new leaves 30 the space between the cap and the bottom of the frame, shown in Fig. 1. On top of said cap is inserted the liner 3. The wedges 4 are slideable on guides 6. The compression springs 5 are first slid onto said guides, after 35 which said wedges, through perforations in the same, are slid over opposite ends of said guides, said springs being centered on the teats 11, and by compressing said springs, the edges of said wedges are inserted into 40 the slots 7 and rest on said liner 3, the position of said liner keeping the pressure of said wedges against the upper surface of said slots. The guides 6 are of a length equal to the distance between the inner edges 45

of the top parts of the frame 1. Of course, 50 when the box is new the said springs are compressed to about the limit, and as the cylinder surface of said cap and frame, as well as the shaft, are worn away by friction, and the counter pressure on said 55 springs lessened, said wedges are forced outward and said cap downward, and any play in the cylinder that would otherwise result from friction is taken up as it occurs, until eventually the springs, wedges and cap 60 would be in the position shown in Fig. 2. The liner 3 is secured to cap 2 by studs 8 screwed through perforations 12 into said cap. The cotter 9 is to prevent said studs 65 from turning.

What I claim is:—

1. An automatic self adjusting shaft box; a movable cap within the frame of said box; a liner secured to the top of said cap; wedges resting on the top of said liner, one on either 70 side and each movable in a slot in the side of said frame, and having perforated flanges; guides for said wedges connecting the upper parts of said frame, compression springs coiled on said guides between the flanges of 75 said wedges.

2. A boltless and self-adjusting automobile shaft-box, formed integral with a supporting rod or beam; a cap movable within the frame of said box; the concavity of said 80 cap and the concavity of the bottom of said frame forming the shaft bearing and leaving a space between the two parts to permit the lowering of said cap; wedges resting on the top of said cap and movable through 85 slots in the sides of said frame; a compensating liner inserted between said cap and said wedges; guides connecting the upper ends of said frame; compression-springs coiled around said guides acting on said 90 wedges.

3. A shaft-box, having a one-piece frame formed integral with a supporting beam; a concave cap movable in said frame and in connection with a concavity in the bottom of 95 said frame, forming a shaft bearing and leaving a space between the two parts to permit the lowering of said cap; wedges so

adjusted in said frame as to rest on said cap and movable through slots in said frame; a liner inserted between said cap and wedges, guides between the open ends of said frame; compression springs coiled on each of said guides to actuate said wedges.

In witness whereof I hereunto affix my

signature in the presence of two subscribing witnesses, this 1st day of August, 1912.

CHARLES THOMAS.
